United States Patent Office.

JAMES CHASE, OF ROCHESTER, NEW YORK.

Letters Patent No. 63,213, dated March 26, 1867.

IMPROVEMENT IN WOOD-TURNING LATHES.

The Schedule referred to in these Letters Patent and making part of the same.

TO ALL WHOM IT MAY CONCERN:

Be it known that I, JAMES CHASE, of Rochester, in the county of Monroe, and State of New York, have invented a new and useful Cutting Apparatus for Wood Lathes; and I do hereby declare that the following is a full, clear, and exact description of the construction and operation of the same, reference being had to the annexed drawings, making a part of this specification, in which—

Figure 1 is a side elevation of a wood lathe provided with my improvements.

Figure 2, a plan of the same.

Figure 3, a diagram representing a cross-section of the carriage and cutters.

Figure 4, a plan of the rotary knife and its frame, detached.

Figures 5 and 6 are end views of the knife, showing modifications of the cutters.

Like letters of reference indicate corresponding parts in all the figures.

My invention has reference more particularly to a rotary knife for cutting ornamental work in wood-turning lathes.

As represented in the drawings, A is the bed of an ordinary wood-turning lathe, B the head-block, and C the tail-block. The bed is provided with ways, *a a*, on which slides a carriage, D, holding the cutters by which the wood is turned. These cutters are three in number—first, a roughing knife, E, stationary in position on the carriage; second, a plain-work knife, G; and third, a circular rotating knife, H, for cutting ornamental work, such as knurl, ogee, or bead. The knives G and H are respectively provided with arms, I and K, both jointed or hinged to an axis, *b*, the former bowing over and resting on a pattern, L, and the latter connecting with a box, M, which has a shaft, N, resting on a pattern, O. The rear end of said shaft has a weight, *c*, for holding it down on the pattern, and the front end has the circular head H, to which the cutters *f* are secured. These cutters are of different kinds and forms, to suit the conditions of the case. Thus, in figs. 3, 4, and 5, the cutters are represented of the regular corrugated form to cut knurl work, and in fig. 6 are represented several forms suited to cut a plain tenon, ogee, and bead work. The cutters are applied to the head in sections 1, 2, 3, being secured by means of screws and slots, *g h*. This enables a portion or whole circle of the cutters to be employed, by which the work in the wood may be at intervals or continuous, as the necessities of the case may require. On the shaft N is secured a pinion, *i*, which gears with a cog-rack, P, extending longitudinally of the lathe, the opposite ends being secured to swinging arms, *k k*, as shown most clearly in fig. 3. By simply raising these arms, the cog-rack will at any time be disengaged from the pinion, and consequently the knife H can be turned or adjusted so as to present its cutters in any desired position to the wood which they cut.

The operation of this machine is as follows: The stick to be turned having been fitted in the lathe, the cutting action is produced by feeding the carriage along on its ways. The roughing knife E takes off the surface, and turns the stick in the form adapted to receive the action of the other knives. The pattern L, on which the arm I of the knife G rests, is arranged on the predetermined formula necessary to turn the plain round work; for instance, in a chair-round or a bedstead post, it will turn the plain cylindrical and tapering portions of the proper form and extent. The irregularities of the pattern, of course, will exactly correspond with the irregularities of the stick. The circular knife H, which cuts the ornamental work, is simply adjusted so that it will commence its cutting action at the proper point of the work by raising the cog-rack from the pinion, as indicated by red lines, (fig. 3,) and turning it around till the right position is reached. Then, by dropping the cog-rack upon the pinion again, the knife will revolve as the carriage is fed forward, and cut to the extent of the cutting edge of the knife. The pattern O, on which the shaft N of the knife rests, is so formed as simply to throw the cutting edge in contact with the stick at the proper position, and has no reference in its particular form to the ornamental form of the work produced in the wood. This is accomplished only by the form of the cutting edge of the knife itself. The extreme diameter of the cutter should not exceed that of the pinion *i*. By the employment of the simply rotating knife as above described, armed with cutters of the proper shape, I am enabled to turn any regular ornamental form in the most expeditious manner and without the peradventure of a mistake. The whole is automatic. The great advantage of this over ordinary fixed knives is at once apparent. Besides this, wherever a change is required I am enabled to secure it in the most simple manner. I can limit the cut exactly as desired by applying the cutters *f* in sections. I can also set the cutters in any position by

raising the swinging cog-rack. And by the combination of the knives G H, I produce a double effect in turning two forms at once. The patterns L O are simply screwed in place, so that their places may be filled readily by others.

In ordinary lathes for turning irregular forms rotary knives are employed, but the axes of such knives usually stand parallel with the stick being turned, and the knives themselves simply revolve rapidly to cut the wood away. It will be noticed that my rotary knife acts in a very different way, for its axis stands at right angles, or nearly so, to the stick being turned, and its turning action is not positive to act as a cutter, but it is simply fed along to produce a continuity or succession of cut, and the cutters stand to act in a manner similar to the ordinary chisel. It will also be noticed that my knife is employed in combination with a sliding carriage that carries it over the wood, and with a pattern that guides its action.

What I claim as my invention, and desire to secure by Letters Patent, is—

1. The employment of a pattern knife or cutter in wood-turning lathes, rotating upon an axis arranged at right angles, or nearly so, to that of the stick or timber which is being turned, and so geared to the frame of the lathe as to leave its pattern upon the stick, substantially in the manner and for the purposes set forth.
2. The employment of the pivoted box M, which constitutes the axial bearing for the knife-journal or shaft N, when the parts are arranged and operate substantially in the manner and for the purposes herein shown and described.

JAMES CHASE.
